UNITED STATES PATENT OFFICE.

BRADFORD WEBSTER, OF LOUISVILLE, KENTUCKY, ASSIGNOR TO WEBSTER LOOSE-LEAF FILING COMPANY, A CORPORATION OF KENTUCKY.

BOOK OR FILING DEVICE.

1,168,447.

Specification of Letters Patent. Patented Jan. 18, 1916.

Application filed January 29, 1910. Serial No. 540,930.

To all whom it may concern:

Be it known that I, BRADFORD WEBSTER, a citizen of the United States, residing at Louisville, in the county of Jefferson and 5 State of Kentucky, have invented a new and useful Book or Filing Device, of which the following is a specification.

My invention relates to books or filing devices, in which leaves are bound on posts 10 or guides; and the object of my invention is to provide a simpler, more durable, and more efficient structure.

The invention consists of novel features and parts and combinations of the same, 15 which will be more fully described herein-after and then pointed out in the claims.

A practical embodiment of the invention is represented in the accompanying drawings which are part hereof and in which 20 similar numerals of reference indicate the corresponding parts in all the views.

Figure 1 is a perspective view of the cover and leaf-retaining portion of the book; Fig. 2 a rear elevation of the book with the 25 back cover removed; Figs. 3 and 4 detail sectional views; Fig. 5, a plan of the locking slide; Fig. 6, a detail view showing the combination between a retaining member and a leaf; Fig. 7, a plan of a leaf; Fig. 8, 30 a perspective view of the pamphlet attachment; Fig. 9, a perspective view of the spring-binding attachment; and Fig. 10 a perspective view of a filling strip.

The book consists of two binding parts, 35 swingingly connected at the rear edges of their bases to a connecting element in the back and to top and bottom covers; of loosely attachable sheets; of loosely attachable filling elements; and of loosely attachable spring-binding elements. One binding part consists of a stiff base 10, having set 40 therein the lockable pins or posts 3 and 4 and being recessed to admit the members 1 and 2. These retaining members 3 and 4 are 45 preferably circular in cross-section, circularly curved so that their axes form quarter circumferences lengthwise, and provided with approximately hemispherical free ends and transverse holes near thereto for admitting the penetrating portions of the locking slide. The other binding part comprises a locking slide 5, a casing 13 therefor, elements 9 for supporting firmly the bars of the casing, and posts 1 and 2. The casing 55 13 is preferably composed of a single piece

or plate bent around in the form of two flat bars with a curved connection on the rear edge. These bars support the casing on top and bottom, are held firmly apart by the elements 9, preferably cylindrical, and are 60 firmly connected by the retaining members 1 and 2 which preferably penetrate said cylindrical elements 9. By penetrating the cylindrical elements 9, the retaining members 1 and 2 are given a very stiff and solid 65 setting foundation through the entire thickness of the casing 13. The curving of the rear portion of the casing 13 especially adapts it as a hinge for the double hinge action when the book is opened for the removal 70 of leaves.

The locking slide 5 is slotted to receive the element 9 and the post 2, thereby slidably holding itself in position. At the inner end of the slide are free projections adapted to 75 hold this end of the slide slidably in position with the assistance of the element 9 and the post 1. By those two sliding engagements the slide 5 is held against any lateral movement. This enables the casing 13 to 80 be of any width and makes it unnecessary to support the slide 5 thereby on either side. The projecting piece 16 is laterally resilient and has a knob for encountering the element 9 around the post 1 as the slide is pulled 85 out. The necessity of overcoming this resilient engagement in pulling out the slide makes it impossible for it to jar loose. The slide is further provided with inside openings for admitting and containing the lockable posts 3 and 4, in which openings are 90 set the penetrating pieces 14 and 15, preferably cylindrical and pointed, for penetrating the transverse holes in posts 3 and 4 and locking the book. To give the proper spring 95 tension and to make the structure simpler, the same inside edge extends around the retaining members 3 and 1.

The outer bar of casing 13 is provided with holes 18, preferably circular, adapted 100 to admit the ends of the retaining members 3 and 4, to pocket and engage them as shown in Fig. 4, and to hold them in exact position laterally and longitudinally to admit the penetrating elements 14 and 15 through 105 their transverse holes. The inner bar of the casing 13 has an opening 17, preferably elliptical, for admitting the post 4 diagonally and a similar opening for post 3. These openings 17 have their minor axes but 110

slightly larger than the diameter of the posts 3 and 4, so that the bar will support the penetrating pieces 14 and 15 immediately after they have penetrated the posts 5 3 and 4.

The posts 1 and 2 are similar in shape to posts 3 and 4, but preferably smaller in cross-section. The smaller the cross-section the less friction there is when the posts 10 1 and 2 pass through the leaves, and the better the operation in opening and closing the binder for removing leaves. The approximately hemispherical free ends are especially important in facilitating the movement of the retaining members through the leaves.

When the book is not entirely filled with leaves, as shown in Fig. 2, the boards 6 of the top and bottom covers respectively have 20 a tendency to tear away from the flexible connection which holds them to the bases 10 and 13. To remedy this defect the bases 10 and 13 are wrapped with flexible pieces 8, which are wrapped around said bases, 25 united at the edges of said bases near the covers and the outside of the book, and the doubled portions are then fastened securely to the inside edges of the covers respectively. This makes it impossible to tear the outer 30 rear edges of the boards 6 away from cover 7.

A single piece of flexible material 7 is used to cover the boards 6 and to connect the two parts. To enable the curved posts 1 and 2, and 3 and 4 to swing into and out of the 35 leaves readily, their axes must remain approximately in the same cylindrical surface. To accomplish this the portion of the cover 7 between the bases 10 and 13 must ordinarily be wider than the chord of the quarter circle on which the posts are curved, which is the thickness of the book inside the 40 covers. To make this extra width small, the bases of the posts 1, 2, 3, and 4, may be set such a distance from the back edges of the bases 10 and 13 that when the free ends of 45 the four posts are in a line, the distance between a line run through the bases of the posts 1 and 2 and a line run through the bases of the posts 3 and 4 will approximately equal the diameter of the circle on 50 whose circumference the posts are curved.

To accomplish this result, the distance of the posts from the back edges of their respective bases should be approximately seven-twenty-fourths of the thickness of the book, making the extra width in the back cover approximately nine-one-hundredths of the thickness of the book. From this it is evident that with books less than two inches thick, the 60 extra width of the back cover would be scarcely noticeable with this arrangement. In case of thick books, to avoid too much metal in the bases, the extra width in the back may be increased to two-tenths the 65 book's thickness, in which case the distance

from the bases of the posts to the swinging edges need only be one-sixth the thickness of the book.

By making the holes 19, 20, 21, and 22 in the leaves 26 elliptical, with their minor axes approximately the diameter of the leaf-retaining members and their major axes approximately four-tenths longer than the minor axes and transverse the leaves, the leaves are held snugly in place whether 70 they are in the middle of the posts (Fig. 6) or at the ends, there is no crumpling of their inside edges, and the passage of the posts through the leaves when the binder is 75 opened is made easier. The ratio just stated 80 between the major and minor axes of these holes is based upon the pins being curved on a quarter circumference and being set with the tangents at an angle of 45° with the bases.

To provide a compact and simple means for spring binding, the strip 11 is used, preferably of wood, provided with holes for admitting the leaf-retaining members of the binder and with a plurality of pieces 25, of 90 resilient material, like soft rubber, of even thickness. To coöperate with this spring-binding strip I employ the filling strip 12.

For filling and binding in law books and the like, I employ the dummy booklet 24, 95 composed of a plurality of leaves fastened together on one edge and provided with holes to admit the leaf-retaining members of the binder. This dummy booklet may have a strip 23 of resilient material for its 100 binding edge.

I do not limit myself to the exact form in which any of the parts of my invention are herein disclosed further than is indicated in the claims which follow:

I claim:

1. A file, comprising leaves and a retaining member; said retaining member passing through some of said leaves obliquely; said leaves being provided with openings adapted to hold them to said retaining member against lateral movement whether said retaining member passes through them obliquely or perpendicularly.

2. A file, comprising leaves and a retaining member; said retaining member being approximately circular in cross-section; and said leaves being provided with openings, whose contour is an ellipse whose minor axis approximates the diameter of the minimum cross-section of said retaining member.

3. A file, comprising leaves, a retaining member, and a base therefor; said retaining member being curved lengthwise and approximately circular in its minimum 125 cross-section; and said leaves being provided with openings whose contour is an ellipse whose minor axis approximates the diameter of said minimum cross-section and whose major axis approximates the major 130

- axis of the maximum section of said retaining member parallel to said base.
4. Leaves, two binding parts therefor, and back cover means for swingingly connecting said binding parts; one of said binding parts having positively fixed therein a perforated retaining member which is curved lengthwise; and the other having positively fixed therein a retaining member curved lengthwise and having a locking mechanism adapted to penetrate said perforated member.
5. Leaves, two binding parts therefor, and back cover means for swingingly connecting the rear edges thereof adapted to allow said edges to move toward and away from each other; one of said binding parts having positively fixed therein a perforated retaining member, and the other having positively fixed therein a retaining member and having a locking mechanism adapted to penetrate said perforated member.
6. Leaves, two binding parts therefor, and back cover means for swingingly connecting the rear edges thereof and adapted to allow said edges to move toward and away from each other; one of said binding parts having a perforated retaining member, and the other having a retaining member and a locking bar adapted both to admit and to penetrate said perforated retaining member.
7. Leaves, a back, and two binding parts connected by said back and hinged thereto; one of said binding parts having one or more curved lockable leaf-retaining members provided with approximately hemispherical ends and being perforated near thereto; and the other having curved leaf-retaining members provided with approximately hemispherical ends and means for penetrating said lockable member or members of the other part.
8. A spring-bound book, having leaves, a loosely attachable spring-binding strip, and means for holding said elements in alignment under pressure; said strip having blocks of resilient material attached thereto.
9. In a filing device, a loosely attachable spring-binding strip, adapted to admit retaining members and provided with blocks of resilient material attached thereto beside said openings.
10. A spring-binding strip, comprising a bar provided with holes and blocks of soft rubber attached thereto.
11. A filing device comprising two binding parts; one of said parts comprising a base and one or more curved lockable leaf-retaining members set therein, and the other comprising a base U-shaped in cross-section with the closed side toward the rear, locking mechanism therein, and one or more curved retaining members set therein; and a back cover connecting said bases and hinged to the rear edges of each.
12. A filing device comprising a lockable leaf-retaining member, a locking mechanism, supporting elements on opposite sides thereof, a member holding said supporting elements positively apart, and leaf-retaining means for connecting and positioning said supporting elements.
13. A filing device comprising a lockable leaf-retaining member, a bar, a member associated therewith, and a locking slide slidably positioned by said member and adapted to grip it resiliently whereby the slide is held at either end of its travel.
14. A filing device comprising a bar, a member associated therewith, a locking slide associated with said bar, adapted to guide itself on said member, and adapted to engage it resiliently to prevent free movement, and a lockable leaf-retaining member.
15. A filing device comprising a bar, a plurality of members associated therewith, a locking slide slidably positioned by said members and adapted to engage one of them resiliently to prevent free movement, and a lockable leaf-retaining member.
16. A filing device comprising a lockable leaf-retaining member, a locking slide, supporting elements on opposite sides thereof, and a member connecting said supporting elements; said slide being adapted to engage said connecting member resiliently.
17. A filing device comprising a lockable leaf-retaining member, a locking mechanism therefor, and supporting elements on opposite sides thereof; one of said supporting elements being adapted to admit said member freely and the other being adapted to pocket the end of said member and to hold it in exact position laterally and longitudinally for said locking mechanism.
18. A filing device comprising a perforated leaf-retaining member, a penetrating locking mechanism therefor, and supporting elements on opposite sides thereof; one of said supporting elements being adapted to admit said member freely and the other being adapted to pocket the end thereof and hold it in exact position for penetration.
19. A filing device comprising a curved lockable leaf-retaining member, a locking mechanism therefor, and supporting elements on opposite sides thereof; one of said supporting elements being adapted to admit said member diagonally and the other being provided with a hole adapted to admit the end of said lockable retaining member to the locking position and there hold it against lateral movement.
20. A filing device comprising two binding parts and a member swingingly connected to each of them and adapted to allow them to move toward and away from each other; one of said parts comprising a base and a plurality of curved lockable leaf-retaining members; the other comprising a

- locking mechanism and supporting elements on opposite sides thereof; one of said supporting elements being adapted to admit said lockable retaining members freely and 5 to guide them to the locking position, and the other being adapted to admit the ends of said lockable retaining members and to stop them in the locking position.
21. A filing device comprising a perforated lockable leaf-retaining member, a locking slide therefor, supporting elements on opposite sides thereof, and a member connecting said supporting elements within said locking slide; said slide having an opening 15 adapted to admit said perforated retaining member freely and to hold itself slidably associated with said connecting member and provided with a finger adapted to penetrate said perforated retaining member.
22. A filing device, comprising a stiff base, a stiff cover, a wrapper flexibly connecting said stiff base to said cover, and an outside cover also flexibly connecting said base and said stiff cover; said wrapper being united with itself at the edge of said base next to said stiff cover and toward the outside of the book and extending diagonally to the inner rear edge of said stiff cover; said outside flexible cover directly 25 connecting the outside adjacent edges of said stiff base and said stiff cover.
23. A filing device, comprising a stiff base, a stiff cover, a wrapper flexibly connecting said stiff base to said cover, and an outside cover also flexibly connecting said 35 base and said stiff cover; said wrapper being united with itself at the edge of said base next to said stiff cover and toward the outside of the book and extending doubled directly to the inner rear edge of said stiff cover; said outside flexible cover directly 40 connecting the outside adjacent edges of said stiff base and said stiff cover.
24. In a filing device, a pair of bases, a pair of cover boards, leaf-retaining members in each of said bases, and a continuous flexible cover connecting said boards respectively to said bases and said bases to each other; said connections between said bases and said covers being doubly reinforced. 45
25. In a filing device, a pair of bases, a pair of cover boards, leaf-retaining means associated with said bases, and a continuous flexible cover connecting said boards respectively to said bases and said bases to each other; said connections between said bases and said covers being doubly and quadruply reinforced. 50
